UNITED STATES PATENT OFFICE

THOMAS S. MCGUIRE, OF CARLISLE, PENNSYLVANIA.

GRINDING-MACHINE.

1,157,647.

Specification of Letters Patent. Patented Apr. 27, 1915.

Application filed July 23, 1914. Serial No. 353,863.

To all whom it may concern:

Be it known that I, THOMAS S. MCGUIRE, a citizen of the United States, and resident of Carlisle, county of Cumberland, State of Pennsylvania, have invented certain new and useful Improvements in Grinding-Machines, of which the following is a specification.

The present invention relates to improvements in grinding devices such as are employed for hand finishing castings and in which the grinding wheel is flexibly supported so that its position may be readily varied by the operator to conform to the variations in the surface upon which it is acting. Devices of this character have heretofore been provided with conduits for conducting dust and fine particles separated from the wheel and casting during the grinding operation to a suction duct whereby a single fan is provided for removing the dust from a plurality of such devices. It is frequently desirable however to operate only one of the grinders and under such circumstances and conditions an unnecessary and wasteful amount of power is consumed in driving the relatively large suction fan, which as above stated must have a capacity sufficient to remove the dust from all of the grinding devices with which it is connected.

With an arrangement whereby a single relatively large suction fan is connected with a plurality of grinders considerable difficulty is experienced in maintaining the necessarily tight connection of the joints of the air or suction conduits. As the position of the grinder must be frequently varied, flexible sections or joints are interposed in the connection between the wheel and suction conduit but these frequently become loose or broken. Furthermore it has been customary to drive such grinding wheels by belts which rapidly deteriorate and in addition to being expensive are continuously exposed and likely to contact with the operator in manipulating the device or when standing or passing close thereto.

The primary object of the present invention is to provide a device of the character referred to in which each grinding wheel will be provided with an independent suction device; and in which instead of employing a flexible belt drive for the grinding wheel, such wheel will be driven by a shaft and gears, all of which are inclosed

so as to be protected from dust and impossible of contact with other objects.

In the accompanying drawings, Figure 1 is a perspective view of a grinding device embodying the present invention; Fig. 2 is a plan view, partly in section of the grinding wheel, its immediate supporting and driving means.

Referring to the drawings, 1 designates a main or line shaft represented as supported in suitable bearings in depending ceiling brackets 2. A hanger comprising top and bottom yokes 3, 4, and an intermediate connecting member 5 is suspended from the shaft 1 and on said shaft within the upper yoke 3 is secured a pulley 6 which is connected by a belt 7 with a pulley 8 on a driving or counter-shaft 9 mounted in bearings in the lower yoke 4. In the embodiment of the invention illustrated the shaft 1 is provided between the arms of the yoke 3, with fast and loose pulleys 10 and 11 with which a main power belt 12 is adapted to operate in the usual manner.

The grinding wheel 13 has its arbor or supporting shaft mounted in bearings carried by the arms of a yoke 14 which is arranged at and forms a continuation of a tubular arm 15 that has a somewhat similar yoke 16 at its opposite end which is supported on the driving shaft 9 so that the grinding wheel and its supporting means may rock about the axis of said counter shaft. On the shaft 9 is secured a bevel gear 17 which meshes with a corresponding gear at one end of a power shaft 18 that has its bearings in the yokes 14, 16, and extends through the tubular arm 15. At its opposite end the shaft 18 is similarly geared, by bevel gears 19, 20 with the arbor of the grinding wheel. On the shaft 9 is also secured a suction fan 21, the casing of which communicates through a passage 22 carried by the yoke 16 with the tubular arm 15 and a similar passage 23 is provided in the yoke 14, one end of which is in communication with the arm 15 and the opposite end of which terminates adjacent the grinding wheel. A hood 24 is arranged over the grinding wheel so that all of the dust and small particles produced by the operation of the device will be caused to pass through the conduit leading from the wheel to the fan casing and will escape from the latter through an outlet 26 which can be connected with any suitable receptacle.

The grinding wheel supporting yoke is so connected with the tubular supporting arm that the operator may readily turn said wheel about the axis of the power shaft 18 5 and as previously described the entire supporting means for the grinding wheel is readily adjustable about the driving shaft 9 being preferably provided with a suitable counterbalancing device in the ordinary 10 manner.

The manner of using and advantages of the device will be understood from the drawing in connection with the foregoing description. It will be seen that the grinding 15 wheel is provided with an independent suction device whereby the dust produced in using the device will be removed with a minimum amount of power; and also that the power shaft 18 and all of the gearing 20 intermediate of the driving shaft 9 and grinding wheel are completely inclosed so that there is no danger of a person's clothing being caught therein or such gearing being affected by dust. The walls of the tubular 25 supporting arm through which the shaft 18 extends will be provided with suitable stuffing boxes so that a substantially air-tight connection will be provided between the grinding wheel and fan casing.

30 Having thus described the invention what is claimed and desired to be secured by Letters-Patent is,

1. In a grinding device, the combination of a power shaft, a hanger suspended from 35 the power shaft and having a yoke at its lower end, a counter-shaft mounted in said yoke, gearing connecting the power shaft and counter shaft, a tubular arm having a yoke at each end, one being supported by the 40 counter-shaft to swing about the axis thereof, a grinding wheel having its arbor mounted in the arms of the yoke at the other end of said tubular arm, a bevel gear on the counter-shaft, a similar gear on the arbor 45 of the grinding wheel, a connecting shaft arranged within the tubular arm and having gears directly engaging those on the grinding wheel arbor and counter-shaft, and a suction fan having its casing in communication 50 with the tubular arm, whereby the driving connection between the counter-shaft

and grinding wheel is completely inclosed and a continuous rigid suction tube extending from the grinding wheel to the fan casing is provided.

55

2. In a grinding device, the combination of a suitable hanger, a driving shaft journaled in bearings at the lower end of the hanger, a tubular arm having at each end a yoke one of which is supported to swing about the axis of said shaft, a grinding wheel mounted on a shaft journaled in bearings in the yoke at the other end of said arm, a shaft extending through the tubular arm and geared directly to both said driving and 60 grinding wheel shafts, and a suction fan having its casing in communication with said tubular arm.

65

3. In a grinding device, the combination of a driving shaft, a tubular arm having at 70 one end a yoke which is supported to swing about the axis of said shaft, a yoke having a tubular head rotatably fitted about the other end of said arm, a grinding wheel having its arbor journaled in bearings on the 75 arms of said second yoke, a bevel gear on the driving shaft, a bevel gear on the grinding wheel arbor, a shaft extending through the tubular arm and provided at its ends with bevel gears meshing with those aforesaid, a hood over the grinding wheel, and a suction fan having its casing in communication with said tubular arm.

80

4. In a grinding device, the combination of a driving shaft, a grinding wheel, gears 85 connected with said shaft and wheel, respectively, a connecting shaft having at its ends gears that engage directly with both said gears, a conduit surrounding said shaft throughout its length, a hood over the grinding wheel, a branch pipe connecting the hood with the main conduit, and a suction fan mounted directly on the driving shaft 90 and having its casing in communication with said main conduit.

95

In testimony whereof I affix my signature in presence of two witnesses.

THOMAS S. McGUIRE.
